RUNNING BOARD

Budd Bronson, Cleveland, Ohio, assignor to The Ohio Rubber Company, Cleveland, Ohio, a corporation of Ohio

Application March 26, 1930. Serial No. 438,958

2 Claims. (Cl. 280—163)

This invention relates to vehicle running boards, and as its principal object aims to provide an improved and durable form of running board which is very attractive in appearance.

5 Further objects and advantages of this invention will be apparent from the following description taken in conjunction with the accompanying sheets of drawings, in which:

Fig. 1 is a top plan view of a running board constructed according to my invention;

10 Fig. 2 is a sectional view taken on line 2—2 of Fig. 1;

Fig. 3 is a top plan view showing another running board constructed according to my invention;

15 Fig. 4 is a sectional view taken on line 4—4 of Fig. 3;

Fig. 5 is a top plan view showing another running board embodying my invention;

20 Fig. 6 is a sectional view taken on line 6—6 of Fig. 5;

Fig. 7 is a top plan view showing still another running board embodying my invention; and

25 Fig. 8 is a sectional view taken on line 8—8 of Fig. 7.

In the drawings, to which I shall now refer in detail, I have shown several composite steel and rubber vehicle running boards constructed according to my invention. It should be understood, however, that while these particular running boards are shown and described in a detailed manner for the purpose of illustration, my invention may also be embodied in composite running boards of various forms and shapes.

30 The running board illustrated in Figs. 1 and 2 comprises a metallic base or body 10 and rubber covering 11 secured thereto by being molded and vulcanized in contact with the metal. The metal body may be of any suitable size and 35 shape, and as here illustrated, is rectangular in form having a substantially horizontally extending top portion 12. At the ends of the metal body, and at the inner side edge thereof which is toward the vehicle body, a continuous raised 40 bead 13 is provided which projects above the surface of the top portion of the metallic body for a distance slightly greater than the thickness of the rubber covering. Along the inner edge of the body the metal is extended downwardly from 45 the bead 13 to provide the longitudinally extending depending flange 14. At the outer edge of the metal body, or in other words at the edge thereof which is away from the vehicle body, the metal is curved or bent to provide the longitudinally extending depending flange 15. As clearly

shown in Fig. 2 the lower portion 16 of this flange extends outwardly beyond the upper portion 17 thereof so as to provide the shoulder 18 at the junction of these upper and lower portions of the flange. The outwardly extending lower portion 60 of this depending flange may be given any desirable shape, and in the running board herein illustrated, the metal at the extreme lower edge of this portion is bent around to form a substantially channel-shaped bead 19.

65 The bead 13 and the depending flanges 14 and 15, as will be readily seen from the drawings, reinforce and materially strengthen the metal body. In addition to this function, these portions also serve to make the running board more 70 attractive in appearance, as will be more fully disclosed hereinafter.

The rubber covering 11 is molded and vulcanized to the surface of the top portion of the metal body, and is carried down upon the rounded portion of the depending flange along the outer edge of the body with the edge of the rubber covering in engagement with the shoulder 18. The rubber thus covers the major portion of the top surface of the metal body leaving the 75 bead 13, and the lower outwardly extending portion of the depending flange 15, exposed or uncovered. The shoulder 18, and the bead 13 along the inner edge of the body and across the ends thereof, protect the edges of the rubber covering 80 so that during use of the running board these edges will not be torn loose from the metal. If desired, during the molding operation, the upper surface of the rubber covering may be provided 85 with any suitable pattern or configuration. Rubber rivets 19' suitably spaced and extending through the metal body, may also be provided as an additional means for securing the rubber covering to the metal.

90 To give the running board an attractive and decorative appearance, the exposed portion of the bead 13, and the exposed outwardly extending lower portion of the depending flange 15, are coated or otherwise treated in any suitable manner with appropriate material to give them a desired decorative appearance. While any suitable material may be applied to these exposed portions of the metal base, I prefer to apply chromium to these portions because of the ability of this material to resist corrosion, and because this 100 material gives the exposed portions of the metal base a hard surface characteristic which tends to resist wear at these points.

105 In Figs. 3 and 4 of the drawings, I have shown another rubber covered running board con-

structed according to my invention. This running board comprises a metallic body 20 and rubber covering 21 secured thereto by being molded and vulcanized in contact with the metal. 5 This form of running board is similar to the form already described in detail in connection with Figs. 1 and 2, differing essentially from that construction only in the shape of the depending flange 22 which extends along the outer edge of 10 the base. As clearly shown in Fig. 4 this flange is so formed that the lower portion thereof extends outwardly beyond the rounded upper portion thereof, a distance which is considerably greater than the thickness of the rubber covering. 15 The wide shoulder 23 thus formed at the junction of the upper and lower portions of the depending flange, is engaged by an edge of the rubber covering which is secured to the top portion of the body and extended down upon the 20 rounded upper portion of the flange. These exposed portions of the depending flange, and the exposed bead 24 which extends along the ends and along the inner edge of the metal body are coated or treated with suitable material, as described in detail in connection with Figs. 1 and 2, 25 so as to provide a desired decorative finish.

In Figs. 5 and 6 of the drawings, I have shown another composite steel and rubber running board embodying my invention. In this form 30 of construction the metal body 25 is formed with a rounded depending flange 26 extending along its outer edge. A raised bead 27 extends across the ends of the body and along the inner side edge thereof. A similar bead 28 formed at the 35 lower edge of the depending flange 26 extends outwardly beyond the upper curved portion of this flange. The beads 27 and 28 together provide the metal body with a substantially continuous raised marginal portion which extends above 40 the surface of the body a distance slightly greater than the thickness of the rubber covering. At intervals intermediate the ends of the metal body, I provide transverse raised beads or ridges 29 which connect the beads 27 and 28 extending 45 along the side edges of the body. These transverse beads divide the surface of the body into a plurality of shallow pan-like sections which extend across the top of the body and down over the rounded portion of the depending flange 26.

50 The major portion of the top surface of the metal body is provided with rubber covering by molding and vulcanizing sheets of rubber 30 in contact with the metal so as to substantially fill the shallow pan-like sections. These sheets of 55 rubber extend across the surface of the body and down upon the rounded upper portion of the depending flange 26 and engage the outwardly extending bead 28, leaving this bead and the beads 27 and 29 exposed. To give the running board a 60 decorative and attractive appearance, these exposed beads extending around the edge of the board, and also the exposed transversely extending beads 29, are coated or treated with a suitable material as already described in detail in connection 65 with Figs. 1 and 4.

In Figs. 7 and 8 I have shown still another running board embodying my invention. In this form of construction I provide a metallic base 31 which is formed with a continuous raised mar-

ginal bead 32 similar to the marginal bead provided on the running board shown in Figs. 5 and 6. This form of construction differs, however, from that described in detail in connection with Figs. 5 and 6, in that the surface of the body is divided into shallow sections by raised beads or ridges 33 which extend longitudinally of the body instead of transversely as shown in Fig. 5. The major portion of the top surface of the board is provided with rubber covering in the form of the rubber sheets 34. These rubber sheets substantially fill the shallow sections and are secured to the body by being molded and vulcanized in contact with the metal. It will be noted that the sheet 35 which extends along the outer edge of the body is carried down upon the depending flange 36 and engages the outwardly extending bead 32 at the lower edge of this flange. The longitudinally extending beads 33, and the marginal bead 32, are left uncovered, and to give the running board a decorative and attractive appearance, these exposed portions are coated or treated with a suitable material to provide the desired decorative finish.

100 In addition to being useful for enhancing the appearance of the running board, the transversely extending and longitudinally extending beads shown in Figs. 5 and 7, also serve as stiffening ribs which strengthen and reinforce the metal body. Furthermore, these raised beads tend to reduce the wear to which the rubber covering is subjected during use and thus prolong the usefulness of the running boards. These beads also tend to prevent lateral movement of the sections of rubber covering relative to the top surface of 105 the metal body, and also protect the edges of the rubber sheets against being torn loose from the metal.

110 It will now be readily seen that I have provided composite running boards of a durable character 115 which are very attractive in appearance, and while I have illustrated and described my invention in a detailed manner, it should be understood, however, that I do not intend to limit myself to the precise details shown and described, 120 but regard my invention as including such changes and modifications as do not involve a departure from the spirit of the invention and the scope of the appended claims.

125 Having thus described my invention, I claim:

1. A running board comprising a metallic body stamped from sheet metal and having integral raised ridges dividing substantially the entire surface thereof into a series of contiguous shallow sections, and sheets of rubber vulcanized to 130 said body so as to substantially fill said sections leaving the top portion of said ridges exposed.

135 2. A running board comprising a sheet metal body having a plurality of integrally formed beads projecting above the surface of the major portion of the body and dividing said surface into a plurality of shallow sections, and a rubber tread disposed in each of said sections and substantially uniformly attached to said body, said sections being in contiguous relation whereby the treads disposed therein provide said body with a 140 rubber covering which is interrupted in continuity only by said beads.

BUDD BRONSON. 145
